RING GATE STRUCTURE

Paul J. Cannell, Hastings, Nebr.

Application May 10, 1937, Serial No. 141,780

7 Claims. (Cl. 251—75)

The object of my invention is to provide a ring gate structure which is simple, durable and comparatively inexpensive to manufacture.

A further object is to provide a ring gate with means for mounting it in a ring gate tower or turbine intake so that vibration is eliminated, yet the ring gate may be easily opened or closed as desired in a facile manner.

Still a further object is to provide mounting means for a ring gate comprising tracks and rollers so arranged that they provide an anti-friction guide means for the ring gate during its telescopic movement from open or closed position relative to the tower.

15 A further object is to provide track and roller means for guiding a ring gate and to tie the rollers together by links which cause their movement simultaneously with each other as the gate is raised or lowered.

20 Still a further object is to provide means to insure movement of the rollers in proportion to the movement of the ring gate, comprising racks and pinions, the racks being carried by a tower and ring gate respectively and the pinions being carried by at least some of the rollers.

25 A further object is to provide means to prevent breakage of the teeth of the pinions during movement of the ring gate.

With these and other objects in view my invention consists in the construction, arrangement and combination of the various parts of my device, whereby the objects contemplated are attained, as hereinafter more fully set forth, pointed out in my claims and illustrated in the 35 accompanying drawings, in which:

Figure 1 is a plan view of a ring gate and the lower portion of a ring gate tower embodying my invention, the upper portion of the tower being shown in section.

40 Figure 2 is an enlarged sectional view on the line 2—2 of Figure 1 showing the gate in closed position, the left side being a section through a portal of the gate and the right side through an outlet elbow thereof.

45 Figure 3 is a diagrammatic view similar to Figure 2 showing a slightly modified construction.

Figure 4 is a view similar to the right side of Figure 2 showing the gate in open position.

50 Figure 5 is an enlarged sectional view on the line 5—5 of Figure 4 showing the coaction of the roller and track means.

Figure 6 is a similar sectional view on the line 6—6 of Figure 4 showing the rack and pinion means for the rollers and tracks; and

Figure 7 illustrates in its upper two-thirds a sectional view on the line 7—7a of Figure 6 and in its lower one-third a similar sectional view on the line 7—7b of Figure 6.

On the accompanying drawings, I have used the reference character T to indicate generally a tower and RG a ring gate. The tower T is usually installed upstream relative to a dam and ordinarily connected by a bridge to the dam crest and spillway, or the tower may be an intake 10 leading to a water turbine. The tower T is provided with a plurality of inlets or portals 10 and an outlet elbow 11, which extends through the dam to the downstream side or to the intake of 15 a turbine.

The ring gate is provided for either fully or partially establishing communication between the portals 10 and the elbow 11. The ring gate RG comprises a cylindrical wall 12 which may be made of boiler plate or the like and is ordinarily 20 reinforced by a plurality of ring stiffeners of I-beam construction, which are omitted from the drawings as they form no part of my present invention. Obviously the cylinder 12 must be reinforced with quite a number of such ring stiffeners. Ring gates are of rather large proportions, the one shown in the drawings being approximately twenty feet in diameter.

Further stiffening is provided by means of radial spokes 13 and 14 at the bottom and top respectively of the cylinder 12 and by angular braces 15 and tie rods 16. The lower edge of the cylinder 12 is provided with a sealing flange 17 adapted for seating against a ring seal 18. The upper edge is somewhat similarly provided with a 35 sealing flange 19 for seating against a ring seal 20.

For opening and closing the ring gate RG a gate stem or lift rod 21 is provided. This extends to the head of the tower (not shown) where suitable mechanism is provided for imparting longitudinal movement to the rod 21 as desired.

40 My mounting means for the ring gate includes ring gate tracks 22 secured to the cylinder 12 at a plurality of positions therearound. By way of 45 illustration, four of the tracks 22 are shown on the drawings and they are placed between four portals 10. Obviously a greater number of portals and tracks may be used for larger ring gates and only three, for instance, may be used 50 for smaller ones, if desired.

Arranged parallel to the ring gate tracks 22 are tower tracks 23 and between the tracks 22 and 23 a roller chain is positioned. The roller chain comprises a plurality of rollers 24 having 55

- stub shafts 25 journaled in link bars 26 at the ends of the rollers as shown in Figure 5. The tracks 22 and 23 are provided with end flanges 27 and 28 to limit endwise movement of the rollers 24. Flanges 26' are provided to retain the rollers against the tracks 23 when the ring gate is raised and prevent their dislodgement from the tracks due to the rush of water through the gate.
- 10 Adjacent the flanges 27 and 28 I provide rack bars 29 and 30. A set of rack bars 29 and 30 is provided for each end of the roller chain. On the ends of at least one roller I secure pinions 31 (see Figure 6). These may be retained in position by lock nuts 32.
- To insure greater safety, I preferably provide the upper two rollers with pinions 31 as shown in Figure 7. The stub shafts 25' for the upper two rollers are not journaled rigidly relative to the link bars 26 but mounted for slight floating movement relative thereto as illustrated.
- 15 The lower half of each stub shaft 25' contacts with a semi-circular seat 33 of the link bar 26 and is normally retained in such position by a bearing block 34 backed by a spring 35. This spring is placed under an initial tension in the neighborhood of five hundred pounds and some play upward of the stub shaft 25' is permitted by the slot-like character of the upper portion of the seat 33 which is indicated at 36.
- 20 Offset from the tracks 22 are extension tracks 37. These are braced relative to the ring gate by annular braces 38. Adjacent the track extensions 25 are tower tracks 39 and between the tracks 37 and 39, rollers, link bars, racks and pinions are provided in the manner already described in connection with the tracks 22 and 23 and as illustrated in Figures 5, 6 and 7. The tracks 37 and 39 it will be noted are offset relative to the tracks 22 and 23 or set farther out from the axis of the ring gate.
- 25 After the ring gate has been assembled in position, any excess play can be taken up between the rollers and tracks by adjustable bolt connections 40, 41 and 42 and by adjusting the lock nuts on the tie rods 16 as required. This reduces the clearance between the parts to a minimum without experiencing any binding or jamming of the gate in its guides during operation and the take-up of the play reduces vibration to a minimum.
- Practical operation*
- Considering the parts in the position of Figure 2, it will be noted that the sealing flanges 17 and 19 are seated against the ring seals 18 and 20. Whenever the gate is moved to open position as in Figure 4, the roller chains will move half as far as the gate actually moves, the travel of the 30 roller chains being positively insured by the rack 29 rotating the pinions 31 and causing them to travel along the racks 30. In the wide open position of the gate at least three of the rollers will remain in contact with each of the tracks 22 and 35 37. During the opening and closing movements, the floating mounting of the upper two rollers prevents any breakage of the pinion teeth due to inaccuracies in machining and the necessary back lash in the teeth.
- 40 45 50 55 60 65 70 75 Without such mounting the ring gate might, in moving back against the rollers during the opening movement, first pinch the bottom rollers and then jam the rack teeth at the top, causing breakage of the teeth. This is particularly true where high head pressures are involved

and where one quadrant of the gate may not balance that of another, thus tending to jam the gate in its guides and cause it to vibrate dangerously.

The floating mounting of the rollers having the pinions permits slight slippage of the rollers in their relative spacings yet the springs 35 cause return of the rollers to their original positions as soon as there is any relief of pressure between the tracks and the rollers. Obviously slight inaccuracies in machining or assembly would permit such relief as it is impossible to provide tracks and rollers which are all so accurate that all of them at all times are in contact with each other. Thus I have made ample provision for proper movement of the rollers and have eliminated all the possibility of their dropping to non-operative positions and at the same time guarded against failure of the rack and pinion mechanism causing the proportional movement of the rollers relative to the gate during its movement from either open or closed position.

In Figure 3 I show diagrammatically a variation of the structure in which the cylinder 12' of the ring gate is mounted exterior of the tower 26, T' rather than within it. The ring seals 18' and 20' are likewise mounted exterior of the tower T', the lower edge of the cylinder 12' seating against the ring seal 18' in the closed position of the ring gate. The upper edge of the cylinder has an inturned sealing flange 19' for seating against the ring seal 20'. The track extensions 37' are offset inwardly rather than outwardly relative to the cylinder 12'. The tower T' is then provided with inlet openings 10' inside the cylinder 12' and located intermediate roller chains as already described in connection with Figure 1. The upper ends of the tracks 37' may be connected together by an annular ring 14' with which a plurality of lift rods 21' are connected. Thus it is obvious that my mounting means for the ring gate may be applied either exteriorly or interiorly of the gate.

Some changes may be made in the construction and arrangements of the parts of my device without departing from the real spirit and purpose of my invention and it is my intention to cover by my claims any modified forms of structure or use of mechanical equivalents which may be reasonably included within their scope.

I claim as my invention:

1. In a ring gate structure, a tower, a ring gate telescopically movable relative thereto and means for mounting said ring gate relative to said tower comprising pairs of tracks carried by said tower positioned diametrically opposite each other, a track spaced from each of said first tracks and carried by said ring gate, roller chains between adjacent tracks and pinion and rack means for moving said roller chains in proportion to the movement of said ring gate relative to said tower.
2. In a ring gate structure, a tower, a ring gate telescopically movable relative thereto and means for mounting said ring gate relative to said tower comprising tracks carried by said tower, a track spaced from each of said first tracks and carried by said ring gate, roller chains between adjacent tracks and adjusting means acting at an angle to the direction of travel of said roller chains for adjusting the spacing between said ring gate tracks and said tower tracks to accommodate the rollers with a minimum of play.
3. In a ring gate structure, a tower, a ring gate telescopically movable relative thereto and means

for mounting said ring gate relative to said tower comprising pairs of tracks carried by said tower around said ring gate positioned diametrically opposite each other, rollers between said tracks 5 and said ring gate, said ring gate having track extensions, other tracks carried by said tower adjacent said track extensions, rollers between said other tracks and said track extensions, and adjusting means between diametrically opposed 10 pairs of tracks for varying the distances between said tracks and the ring gate to provide a snug rolling fit between surfaces in contact with the rollers.

4. In a ring gate structure, a tower, a ring gate 15 telescopically movable relative thereto and means for mounting said ring gate relative to said tower comprising a plurality of tracks carried by said tower and positioned at intervals around said ring gate, tracks in said ring gate and rollers 20 between said tower tracks and said ring gate tracks, track extensions on said ring gate offset relative to said first tracks, other tracks carried by said tower adjacent said track extensions, and rollers between said other tracks and said track 25 extensions.

5. In a ring gate structure, a tower having an intake and an outlet, a pair of seats surrounding said tower, a ring gate seating against said seats and means for mounting said ring gate comprising 30 a plurality of tracks positioned in pairs diametrically opposite each other on the exterior of said tower, a plurality of tracks on the interior of said ring gate and rollers between said tower and ring gate tracks.

6. In a ring gate structure a casing having a passage therethrough, a ring gate movable relative thereto for opening and closing the passage and means for mounting the ring gate upon the casing comprising a track on the casing, guide 5 racks at the side thereof and a chain of rollers in the track in contact with the surface of the ring gate there adjacent, said chain including links rotatably holding said rollers together to shift as a unit and pinions on some of said rollers meshing with the guide racks, each of the pinion bearing links being provided adjacent the pinion with an elongated aperture for journaling the roller including a block spring pressed against said roller to permit a slight longitudinal shift 10 of the axis thereof and adapted thereby to insure at all times a positive mesh of the pinion in the rack.

7. In a ring gate structure, a tower, a ring gate 15 telescopically movable relative thereto and means for mounting said ring gate relative to said tower comprising pairs of tracks carried by said tower and positioned diametrically opposite each other, a track spaced from each of said first tracks and carried by said ring gate, roller chains between 20 adjacent tracks, pinion and rack means for moving said roller chains in proportion to the movement of said ring gate relative to said tower, the pinions of said pinion and rack means being carried by said roller chains and movable within 25 predetermined limits relative thereto, and resilient means for suspending said roller chains relative to said pinion and rack means.

PAUL J. CANNELL.
